UNITED STATES PATENT OFFICE.

SAMUEL S. FRETZ, OF PHILADELPHIA, PENNSYLVANIA.

SELF CLOSING AND FOLDING UMBRELLA.

1,113,769.

Specification of Letters Patent. Patented Oct. 13, 1914.

Application filed February 18, 1913. Serial No. 749,075.

To all whom it may concern:

Be it known that I, SAMUEL S. FRETZ, a citizen of the United States, residing in the city and county of Philadelphia, State of Pennsylvania, have invented a new and useful Self Closing and Folding Umbrella, of which the following is a specification.

My invention consists of an umbrella (or a parasol) in which provision is made for the self-closing of the same by the release of what is known as the lower spring or spring catch when the runner that has held the umbrella (or parasol) in open position operates what is known as the upper spring or spring catch so as to release said runner, when the latter subjected to the strain of the cover and frame, is rendered free to slide on the stick to the closed position of the umbrella (or parasol), carrying said cover and frame with it to said position.

It consists further in providing a folding umbrella with a stick of tubular members telescopically fitted one with the other and connecting an upper spring or spring catch connected with the inner stick member whereby in folding the umbrella (or parasol) the inner member when drawn out of the exterior member, said spring or spring catch is carried by said member, thus avoiding the lengthened slot in the inner member as heretofore occasioned when said spring or spring catch is attached to the outer stick member.

The invention is satisfactorily illustrated in the accompanying drawing, but the important instrumentalities thereof may be varied, and so it is to be understood that the invention is not limited to the specific arrangement and organization shown and described.

Figure 1 represents a longitudinal section of portions of an umbrella embodying my invention. Figs. 2, 3, 4, and 5 represent longitudinal sections of different parts thereof. Fig. 6 represents a side elevation of a detached portion thereof. Fig. 7 represents a longitudinal section of portions of the umbrella in condition preparatory to folding. Fig. 8 represents a side elevation of portions of the umbrella in folded condition.

Similar numerals of reference indicate corresponding parts in the figures:—

Referring to the drawings:—1 designates what is termed an umbrella stick or staff, the same being formed of tubular members

2 and 3 fitted telescopically one within the other, the outer member being comparatively rigid from end to end, and the inner member being formed with a folded section 4 which is pivoted thereon by the link 5, as at 6, the umbrella handle 7, being connected with the end of the section 4.

8 designates the upper spring or spring catch, the same having its shank within the inner member 3 and connected therewith by the teat 9 which is formed in the lower end of said shank and adapted to enter an opening in said inner member as most plainly shown in Figs. 2 and 4, said spring having a nose 10 which is adapted to protrude through slots 11 and 12 in the inner and outer members of the stick so that its top is engaged by the shoulder 13 on the interior of the upper portion of the sliding bulb runner 14, this being occasioned when the umbrella is in open condition, see Fig. 2, it being noticed that said runner has a shoulder 15 on the interior of its lower portion for engagement with the nose 16 of the lower spring or spring catch 17 of the stick when the umbrella is in closed position see Fig. 3. It will be noticed that said lower spring has its nose 16 attached to the inner member of the stick, and it is provided with a head 18, the two members of the stick having openings 19 and 20 therein to permit the protrusion of the nose 16 therethrough, and openings 21 and 22 therein to permit the protrusion of the head 18 therethrough, it being noticed also that said head extends outwardly from the stick to a greater extent than said nose 16, consequently when the nose is pushed into the stick by the action of the runner 14, so as to permit the latter to open the umbrella, the head 18 remains partly in the openings 21 and 22, and so engaged more particularly with the outer stick member, whereby the disconnection of the two stick members is prevented in the opening of the umbrella, attention being directed to the fact that the lower end of the opening 21 of the outer member is closed from below by the base wall 23 which is an integral portion of the outer member at what may be termed the lower end of said member, consequently the head 18 rests solidly on the top of said wall and so cannot be pulled downwardly through the latter when the runner is raised by one hand and the handle is held by the other hand, and thus the two members re-

main locked in the opening of the umbrella, but when it is desired to fold the umbrella, the latter being in closed condition, the head 18 is pushed into fullest extent when it 5 clears the inner side of the top of the opening 21 at the back of the wall 23. Then, when the inner stick member is drawn out, said head rides down said back and the nose of the lower catch pressed into the inner 10 stick member by the operation of the head 18, causing the entire lower catch to follow the inner stick member and emerge from the outer stick member when the parts are in 15 position to be folded as shown in Fig. 7.

15 When the umbrella is in open condition the runner rests on the nose of the upper spring, see Fig. 2, while the head of the lower spring rests in the openings of the inner and outer stick members, see Fig. 3, consequently the umbrella is held or controlled 20 doubly in its open condition, but when the umbrella is to be closed the lower catch is pressed in to the head thereof whereby the inner stick member is no longer sustained by 25 the lower catch on the outer stick member, consequently, the downward strain or tension of the cover of the umbrella and the frame, *i. e.* the ribs and stretchers, presses the runner forcibly against the outer corner 30 of the nose of the upper spring, overcoming the holding action of the latter whereby the shoulder 13 of the runner presses the nose of the spring sidewise inwardly whereby the runner rides freely downwardly over said 35 spring to its lowermost position, folding the cover and frame, and so closing the umbrella, which as is apparent, has been automatic or self closing in its nature.

40 In order to facilitate the inner movement of the head of the lower catch, the wall of the opening 21 of the outer stick is depressed or recessed as at 24, whereby the contiguous portion of the thumb of the carrier of the umbrella on said head may press in the latter to an extent to cause said head to fully 45 clear the outer stick when so required. It will be noticed also that the upper spring is connected with the inner stick member whereby when the latter is drawn out from 50 the outer stick member in the operation of the folding of the umbrella, the nose of said spring rides on the lower wall of the opening 12 in the outer member and so enters the inner stick member, and recedes from the 55 outer stick member, thus avoiding a long

slot in the outer stick to pass said nose as is the case where said upper spring is connected with the outer stick member, such slot highly weakened the wall of the inner stick member.

Having thus described my invention what I claim as new and desire to secure by Letters Patent, is:—

1. In an umbrella, a stick composed of inner and outer members telescopically arranged one within the other, upper and lower catches on said stick, and attached at one end to the inner members of said stick, a runner, a head on the lower catch separated from the nose thereof, the outer stick member having an opening through which said head is protrudable, a portion of the outer stick member forming a seat for the head and closing said opening below, whereby the umbrella is held in open condition by the action of the runner on the upper catch and said head of the lower catch on said portion, and is adapted to be automatically released and closed by inward motion imparted to said head, thus releasing the inner stick member and permitting the runner to automatically force in the upper catch causing the automatic folding of the umbrella, said upper catch being constructed to recede from the outer member and enter the inner member in the operation of folding of the umbrella.

2. In an umbrella, a stick composed of telescopic members, upper and lower spring catches attached at one end to the inner member of said stick, the outer member being comparatively rigid throughout its length and the inner member formed with a folding section, the upper catch having a nose adapted to protrude through openings in the inner and outer members, the lower catch having a nose and a head extendable through separate openings in the inner and outer members, said head extending to a greater extent than said nose, and a runner movable on the outer member of the stick and engageable with said nose without withdrawing the head from its engagement in the openings of the inner and outer members.

SAMUEL S. FRETZ.
